WRINGER

Carl Moon, Detroit, Mich.

Continuation of application Serial No. 505,318,
December 29, 1930. This application February
8, 1939, Serial No. 255,238

55 Claims. (Cl. 68—249)

This invention, while directed generally to laundry machines in which clothes pass between operating rollers, is exemplified herein as a clothes wringer.

Power wringers involve many problems. In the ordinary operation of a clothes wringer the person using the wringer is concerned with several functional requirements.

Objects of the invention are to satisfy these requirements, and involve the following features:

The control—starting, stopping and reversing—of the driving mechanism.

The control of the pressure on the rolls involving a quick or safety release of that pressure.

The resetting of the pressure and preferably, also, a normal adjustment of the pressure.

Movability of the wringer to different adjusted positions of use, commonly referred to as indexing.

Wringers as now commonly in use are usually provided with one or the other of two general schemes going to the safety of the operation. In one of these, provision is made for stopping the rolls so as to prevent a further injuring of the part caught and in some cases actually reversing the roll so as not to limit the indrawing action but also to expel the part caught. The other type of safety device provides for releasing the pressure on the rolls so that notwithstanding continued rotation, the pressure being released, further serious injury is obviated or the injury very greatly reduced.

Various means for actuating these safety devices have been developed, some of them providing a manual tripping or actuating mechanism which is actuated by the operator to initiate a relief action.

In the present invention means are provided for manual actuation of both release devices and for resetting them, both of these safety devices being actuated or responsive to a single releasing effort by the operator.

The present invention contemplates, also, a second method of actuating the release devices, this method being usually referred to in the art as the instinctive method of release. An operator when caught in the wringer instinctively draws back in the effort to prevent further in-drawing of the part engaged to pull the part free from the engagement. In the present invention the wringer frame is mounted to respond to such a pull (or push) and to effect both a release of the pressure and a release or disengagement of the driving means so that not only the pressure

on the rolls is released but the continued rotation of the rolls is also stopped.

The wringer is provided with an indexing mechanism by which the wringer is locked at different angles. As developed in the present wringer this locking of the indexing mechanism is accomplished automatically with the resetting of the driving mechanism and the wringer pressure.

10 In order that the wringer itself may be positioned so as to yield in response to an instinctive pull of the operator when caught it is yieldingly held at the index position so that it can respond to such a pull and thus effect a release. The wringer, therefore, must be positioned so as to permit this yielding movement and if it is to be responsive to a push as well as a pull it must be centered with relation to its wringing position and yieldingly held at that position with sufficient force to prevent accidental movement in the ordinary wringer operation. In the present device this centering and this yielding holding of the wringer in its operating position are automatically accomplished by the resetting mechanism as it resets the pressure and resets the driving mechanism. Inasmuch as in the feeding of clothes to the wringer it is more apt to involve the pushing of the wringer away from the operator while the instinctive action of a user caught in the rolls is usually a pull rather than a push, it is desirable to make the releasing movement of the wringer more sensitive to a pull than a push by the operator. In the present invention this is accomplished.

35 In carrying forward the invention and effecting a simplification of these different features, all these different functions are accomplished through the same general operating member which, as specifically shown, is in the form of a rotative rod extending across the bottom of the wringer with handles at each end of the wringer operative in either direction, the rotative action of the rod relocking the indexing device, resetting the yielding centering device, resetting the pressure on the rolls, and re-engaging the driving mechanism. Further features and details of the invention will appear from the specification and claims.

40 45 50 A preferred embodiment of the invention is illustrated in the accompanying drawings as follows:

Fig. 1 shows a front elevation of the wringer partly in section, the clutch being shown in one of the driving positions and the clutch control lever being shown in dotted lines in the neutral

position; corresponding positions of the other parts have not been shown in dotted lines.

Fig. 2 a section on the line 2—2 in Fig. 1.

Fig. 3 shows a section on the line 3—3 in Fig. 1 with the parts in pressure setting relation.

Fig. 4 a section on the line 4—4 in Fig. 1.

Fig. 5 a section on the line 5—5 in Fig. 1.

Fig. 6 a view partly in section on the line 6—6 in Fig. 1.

Fig. 7 an end view of the wringer head.

Fig. 8 a section on the line 8—8 in Fig. 1.

Fig. 9 a section on the line 9—9 in Fig. 1.

Fig. 10 a section on the line 10—10 in Fig. 1.

Fig. 11 a section similar to that of Fig. 3 but with the parts in pressure release position.

Fig. 12 shows an end view of a fragment of a wringer frame.

10 marks the head of the wringer in which the driving gears are arranged. The head is provided with a swivel extension 11 which is received in the upper end of the usual post 12 which carries the wringer. A vertical drive shaft 13 extends upwardly through the post from some source of power, ordinarily the power that drives the washing machine to which the wringer is attached. This shaft extends through bearing supports 14 and 15 at the bottom and top of the head respectively.

Bevel gears 16 and 17 are journaled on the shaft 13 and these gears continuously mesh a bevel gear 18. The gear 18 has an extended hub 44 which is journaled in a bearing formed in a frame 19. The frame has the connected arms 20 and 21 and these arms are carried by a gear frame support 22, the support 22 being swiveled in the extension 11 of the head and the arms 20 and 21 being rotatively related to the shaft 13. With this arrangement the wringer head may be swung relatively to the gear frame and the head swung relatively to the post 12 for indexing.

A clutch block 23 has detents 23a on its ends adapted to engage detents 16a and 17a on the bevel gears 16 and 17. The block is splined on the shaft 13 so that while it is locked against rotation on the shaft it is movable axially on the shaft to set and release the clutches. The block has a circumferential groove which receives the bifurcated ends of an operating bar 24. The operating bar terminates in an eccentric strap 24a which is actuated by a crank 25a fixed on a shaft 25. The shaft 25 is journaled in a bearing 26 extending from the head and is provided with a manually operative lever arm 27 at the inner end of the head by means of which the shaft may be rocked, the crank operated, the bar 24 actuated, and the clutch block moved to release the driving connection or reverse the same in the usual manner. The shaft 25 is continued or projected by means of a shaft 28, the shaft 28 being connected with the shaft 25 by a ring 29, the ring encircling the vertical shaft 13. Thus the ring permits of placing the shafts 28 and 25 at the direct center of the wringer and permits of a controlling shaft extending from end to end of the wringer.

In order to index the wringer, that is, lock the head and consequently the wringer frame with the post 12, I provide the following mechanism: A pawl 30 is pivoted on the gear frame support 22 by means of a pivot pin 31. The pawl extends through a slot 10a in the swivel extension 11 of the head, the outer surface of the pawl gradually increasing the radial spacing from the pivot 31 providing a wedging engagement with the post. The inner side of the slot 10a has sufficient cir-

cumferential length to permit of pivotal movement of the swivel extension. The pawl has an upper face 30a which is adapted to be engaged by either of the cam surfaces 33 arranged on the face of the cam plate 32 the support 22 having the notch 22a affording clearance for the cam plate. The cam plate 32 is fixed on the shaft 25 and is, therefore, adapted to be rocked by either the shaft 25 or shaft 28.

10 This pawl and cam mechanism effects two important functions: The cam forces the pawl into wedging engagement with the inner surface of the post, locking the gear frame rigidly with the post. At the same time the frictional engagement of the engaged cam surfaces 33 with the surface 30a of the pawl yieldingly secures the head against movement in the normal wringing operation but permits a yielding movement in response to an instinctive pull of an operator. 15 This variation in engagement of the pawl with the post and the yielding resistance afforded by the cam on the surface 30a are brought about by the fact of the wedging arrangement of the engaging surface of the pawl with the post, the greater leverage afforded at the engaging surface 30a over that of the engaging surface of the pawl with relation to the pivot, and also the difference in radial position of the engaging surfaces between the pawl and the post and the friction surfaces of the cam 33 and the surface 30a, this difference being sufficiently marked to substantially lock the gear frame at the index position and yieldingly hold the wringer head at the set or operative position. As will be herein-20 after explained, when the wringer is pulled for instinctive release the engaged cam 33 rolls out of engagement with the turning of the shaft 25 and thus makes the instinctive pull movement more sensitive than a release from pushing the wringer.

25 The main wringer frame has a base 34, and side stiles 34a. The base has projections 34b and 34c carrying bearings for the rod 28. The base 34 also has the flaring front and rear cross members 35 connected by a trough 36 provided with a drainage opening 37 (see Fig. 4).

30 A water board 38 is pivotally mounted at 39 on the control rod 28. Flipper arms 40 and 41 are fixed on the shaft 28, these arms being spaced relatively to the water-board to afford some lost motion, but to swing the water board to reverse position when the control rod 28 is thrown to reverse position.

35 The wringer is provided with a lower wringer roll 42. The wringer roll has a shaft 42a and this shaft is journaled in bearings fixed in stiles 34a. The shaft 42a is connected by a flexible coupling 43 with the hub 44 of the gear 18. The flexible coupling 43 is made up of a series of discs connected at separated points, each pair of discs being connected at off-set points from that of the adjacent pair of discs in the well known manner of flexible couplings. This flexible coupling provides sufficient flexibility to permit the wringer to swing relatively to the gear frame and post 12 in response to an instinctive pull of the operator, and tends to maintain the wringer on center.

40 A top frame member 45 is carried by the main frame and is free to move upwardly relatively thereto. An upper roll 46 is mounted in the top frame member and provided with the usual bearings 46a (Fig. 1) which are slidingly mounted in the top frame member. The assembly of the upper roll and its bearings are retained by cross screws 48a in the top frame and pressure is ex-

erted on the rolls from the top frame by means of a spring 47 the ends of which rest on the top bearings. The upper frame 45 is pivotally connected at either side as at 50 to downwardly projecting plates 51, the same perhaps being best shown in Figs. 3 and 11. The upper frame and its attached parts may be swung on the pivot 50 either to the front or rear, as shown in broken lines in Fig. 4, so that by removing the screws 45a, the upper roll with its bearings 46a may be removed from the upper frame. In the dotted line position (Fig. 4), the upper roll has been removed. Guard plates 42c are arranged at the ends of the rolls and are journaled on the shaft of the lower roll. When the upper frame is swung out, the guard plate can swing out to the position shown in dotted lines in Fig. 4 to permit the release of the upper roll. The pressure member is adjusted by screw 48 arranged in the top frame member and secured to the spring 47 in the usual manner (see Fig. 4). A guide bar 42b is secured to the guard plates and extends in front of the bite of the rolls on one side of the wringer.

The wringer head is provided with a flange where it engages the wringer frame and screws 49 extend through this flange into the wringer frame, thus rigidly securing the head to the wringer frame.

The top frame member is secured to plates 51 (one at each end of the wringer) by screws 50. These plates extend downwardly through the top frame member and stiles 34a to the bottom of the wringer and are slidably mounted in the stiles 34a. The lower ends of the plates 51 are enlarged at 52 and are provided with cam slots 53.

Rock arms 56 are mounted on the shaft 28 and are locked with the shaft by pins 54 and 55. These arms have at each end, heads 57, in which are mounted pins 58 and 59 which are adapted to engage the cam surfaces of the slots 53.

The plates 51 are provided with slots 60 through which the rod 28 extends and this provides the clearance of the up and down movement for the plates 51.

When the rod 28 is swung to its extreme in either direction one of the pins 58 or 59 at each end of the wringer is brought into engagement with the cam surface at the bottom of the slot 53 and thus depresses the plates 51 and with them the top frame member 45, bringing the frame down to set position and restoring the pressure through the spring 47 on the rolls. It will be noted that in this set position the pin (59 as shown in Fig. 3) is directly below the rod 28, so that it may be said to be on center and not only is held in this position by the frictional engagement of the pin 59 with the cam surface of the slot but is locked by the engagement of the cam surfaces 33 on the pawl 30. When the lever arm 27 is swung, therefore, it is only necessary to start the pin 59 to carry it off center and from there on the pressure effort of the spring 47 continues the rotative movement of the rod 28 until the pressure of the spring 47 is relieved. The spring 47, therefore, through its energy operating through the rod 28, completes the release of the cams 33 and consequently completes the release of the indexing of the wringer, and also supplies energy to throw the clutch block 23 to neutral position midway between the gears 16, 17 at which time the clutch control lever 27 is moved to the dotted line position of Fig. 1. When it is desired to reset the pressure on the spring it is only necessary to rock the arm or lever 27, thus swinging the rod 28 to bring either the pin 58 or

59 to the position in the alignment with the rod 28. This draws down the plates, sets the top frame member and resets the pressure on the spring. This is accomplished without changing the pressure adjustment through the screw 48.

Springs 61 have their upper ends secured to projections 62 extending inwardly from plates secured to the lower frame, and in their lower ends to pins 63 secured in the plates 51 so that when the plates are released from the action of the pins 58 or 59 the springs 61 carry the top frame upwardly to the limit of its movement even though the pressure exerted by the spring 47 has ceased to operate.

In order to more securely lock the frame members together when the wringer is in set position the sides of the upper frame are provided with projections 45a which extend into notches 34d at the tops of the stiles 34a. This positively centers and holds the upper frame in register with the lower frame, thus supplementing the plates 51 in holding the parts rigidly with the wringer in set position.

In order that control of the wringer may be more conveniently accessible I prefer to provide a lever 64 on the outer end of the rod 28 so that the control and resetting of the wringer may be accomplished by either hand and from either end of the wringer.

In order that the safety devices may be actuated through an instinctive pull on the wringer the following mechanism is provided: A collar 65 is fixed on the shaft 28 within the head 10 the walls of the head being projected at 10b to provide space for the collar 65, the projection having a cavity permitting the swinging of the head relatively to the shaft 28 and hub 65. Arms 66 project from the collar 65. The frame 19 is provided with a slot 67. The vertical side walls 67a of the slot form operating surfaces engaged by the arms 66 (see Figs. 6, 8, 9, and 10). As the resetting levers 27 and 64 are swung the arms 66 are swung into engagement with the surfaces 67a and center the wringer head, and consequently the wringer, with the frame 19. This same setting action, it will be remembered, locks the frame with the post, but the yielding nature of the engagement of the cams 33 with the pawl 30 permits movement of the wringer on the post in this centering operation so that as the drive is reset through the rotation of the rod for drive in either direction the arms 66 swing to the opposed surfaces 67a and positively center the wringer with relation to the frame and post. If the wringer is swung either forward or back, one or the other of the arms 66 is forced by one of the moving surfaces 67a (the frame 19 being held by the lock at the index and the head 10 being slotted at 10a) toward the upright or vertical direction and this movement of the arms 66 rocks the arm 28 starting the release movement by moving the pin 59 off center with the resulting neutralizing movement of the clutch, release of the index, the release of the wringer with relation to the gear frame, and release of the pressure on the rolls. It will be noted if the wringer is pulled (moved to the right in Fig. 3) and the cam 33 being at the opposite side of the axis of the head moves toward the left and the counter-clockwise rotation of shafts 28 and 25 swinging pin 59 off center results in a rolling movement of cam 33 out of engagement while a push of the wringer (movement toward the left in Fig. 3) also moves the shaft in a counter-clockwise direction, but the cam 33 slides on the surface 30a counter to

the direction of movement. Thus the instinctive pull release movement is sensitive while the push release movement is less sensitive and therefore less liable to effect an accidental release movement through the feeding of clothes to the wringer.

It will be seen, therefore, that in this structure through this single main operating member, namely, the rod 28, the entire control of the safety devices, pressure and drive, is accomplished. With this simple mechanism it will be noted that all the controls are carried through the bottom of the wringer and are responsive to the operation of a single member, namely the operating rod, actuated consciously through the operating handles or instinctively through a pull on the wringer. This is responsive to the manual control through the handles or an instinctive control through swinging of the head, and through the actual operation of this rod the pressure on the wringer may be reset, the gears set to give the rolls either direction of movement, the indexing locked, the wringer yieldingly centered, the instinctive release mechanism positioned to be operated by movement of the wringer either forward or back, and the water board is automatically reset to operate with relation to direction of movement of the rolls. The manual release levers are arranged at both ends of the wringer so that the operator may handle either one that may be the more convenient. The resetting mechanism is utilized in the release operation, but the resetting operation and release operation may be accomplished by different means, manually by the lever, or instinctively through the action of the arms 66.

It will be noted that the engagement of the pin 59 in set position is practically point engagement and that under the ordinary jar of the wringer is unstable and that the holding means incident to the member 32 not only holds the mechanism in set position, but also under normal conditions would be effective for releasing the pressure means upon a movement of the wringer. The parts 65-66 supplement the holding means in this regard and not only, under ordinary conditions, effect a release but go farther and compel a movement of the rod and therefore assure a positive release.

In the operation of the wringer, starting with set position, should the operator become caught in the rolls, a mere pull or push, ordinarily a pull, swings the wringer frame. This compels a rotation of the releasing rod positively accomplished by the arms 66 and the action of the cam plate 32 in carrying the pin 58 or 59, as the case may be, off center and thus releasing the pressure on the rolls. This same action of the rod acting through the crank or eccentric 25a and bar 24 moves the clutch to neutral. This same action releases the indexing lock.

To reset the wringer, all that is necessary is to operate one of the levers 27 and 64, thus rotating the rod. This, through the rock arms 56, resets the pressure, through the eccentric 25a and bar 24, sets the clutch in driving relation, compels a movement of the wringer to centered position, locks the wringer in this position, and locks the index.

It will be noted that after the release, the detents 45a free the top part of the frame so that it may swing out and increase the opening movement of the rolls.

The present application is a continuation of 75

application 505,318 filed by me December 29, 1930, for improvement in Wringers.

What I claim as new is:

1. A wringer mechanism or the like including in combination a wringer frame and head rotatably supported on a wringer post, cooperating rolls mounted in said wringer frame, a drive mechanism including a second frame member pivotally mounted in said head, lock mechanism on said second frame member to lock same on the wringer post, a control shaft pivotally mounted in said wringer frame and head extending the full length thereof, a hand lever mounted on each end of said control shaft, mechanism in said wringer and head operable by rotation of said control shaft to apply and release roll pressure, lock and release the frame lock, and stop and start rotation of the wringer rolls, a flexible coupling between the drive mechanism and driven roll permitting pivotal movement of the wringer frame and head with respect to said second frame and mechanism operable by said relative movement to rotate the control shaft whereby manual rotative movement of the wringer and head on the support post releases pressure on the rolls and stops the rotation of same.

2. A wringer mechanism or the like including in combination a wringer frame and head rotatably supported on a wringer post, cooperating rolls mounted in said wringer frame, a drive mechanism including a second frame member pivotally mounted in said head, lock mechanism on said second frame to lock same on the wringer post, a control shaft pivotally mounted in said wringer frame and head extending the full length thereof, mechanism in said wringer frame and head operable by rotation of said control shaft to apply and release roll pressure, lock and release the frame lock, and stop and start rotation of wringer rolls, a flexible coupling between the drive mechanism and driven roll permitting pivotal movement of the wringer with respect to said frame, mechanism operable by said relative movement to rotate the control shaft whereby manual rotative movement of the wringer and head on the support post releases pressure on the rolls and stops rotation of same, and hand levers mounted on the ends of said control shaft to rotate same whereby roll pressure is re-set, the wringer rolls rotated, the wringer locked on the support post and the mechanism frame realigned with the wringer in position for safety release by manual rotative movement of the wringer with respect to the post.

3. In a wringer or the like of the type having an emergency release for the rolls thereof, driving means therefor having a releasable connection therein; a frame movable with respect to the driving means; means responsive to relative movement of the frame and driving means for operating the emergency release; cooperating rolls associated with the frame; a pressure mechanism for the rolls; means for latching the driving means in operative position with the frame, a release device for said latching means operable by relative movement between the head and driving means and including a manually operated rotatable rod member for resetting pressure following actuation of the release mechanism and automatically resetting the connection to control the wringer drive.

4. A wringer or the like of the type having an emergency release for the rolls thereof, including driving means for the rolls having a re-

leasable connection therein, a frame, rolls associated with the frame, a pressure mechanism for the rolls, a rod disposed longitudinally of and rotatable in the frame, means cooperating between the pressure mechanism and said rod whereby rotation of the rod in one direction causes actuation of the pressure mechanism to press the rolls together, locking mechanism operative to hold the rod in pressure position, releasable through the reverse rotation of the rod, and means between the rod and releasable connection whereby reverse rotation of the rod causes actuation of the releasable connection to stop the rolls.

5. In a wringer or the like, a frame; a pair of wringer rolls mounted in the frame; a pressure means exerting pressure on the rolls; a re-setting device for re-setting the pressure on the pressure means comprising members in thrust relation with each other and having connections with points of thrust engagement between them and the pressure means and the frame, one of the members being swingingly mounted and swinging on a fixed center to set the pressure means and through its swinging increasing the thrust on the pressure means as the points of thrust engagement of the members approach centering alignment with the direction of thrust, said device having a manually engageable part for moving the members relatively to set position; and a separate manually responsive release device initiating a safety release of the pressure means.

6. In a wringer or the like, a frame; a pair of rolls mounted in the frame; a pressure means exerting pressure on the rolls; a re-setting mechanism for re-setting the pressure on the pressure means comprising members in thrust relation with each other and having connections with points of thrust engagement between them and the pressure means and the frame, one of the members being swingingly mounted and swinging on a fixed center to set the pressure means and through its swinging increase the thrust on the pressure means as the points of thrust engagement between the members approach centering alignment with the direction of thrust, with the final setting position placing the thrust members in unstable relation under conditions of use with the points of engagement at or adjacent to alignment; holding means holding the members in set position; and devices releasing the holding means to facilitate a release movement of the thrust members.

7. In a wringer or the like, a frame; a pair of rolls mounted in the frame; a pressure means exerting pressure on the rolls; a re-setting mechanism for re-setting the pressure on the pressure means comprising members in thrust relation with each other and having connections with points of thrust engagement between them and pressure means and the frame, one of the members being swingingly mounted and swinging on a fixed center to set the pressure means and through its swinging increase the thrust on the pressure means as the points of thrust engagement between the members approach centering alignment with the direction of thrust, with the final setting position placing the thrust members in unstable relation under conditions of use with the points of engagement at or adjacent to alignment; holding means frictionally engaged holding the members in set position; and devices releasing the holding means to facilitate a release movement of the thrust members.

8. In a wringer or the like, a frame; a pair of

rolls mounted in the frame; a pressure means exerting pressure on the rolls; a re-setting mechanism for re-setting the pressure on the pressure means comprising members in thrust relation with each other and having connections with points of thrust engagement between them and the pressure means and the frame, one of the members being swingingly mounted and swinging on a fixed center to set the pressure means and through its swinging increase the thrust on the pressure means as the points of thrust engagement between the members approach centering alignment with the direction of thrust, with the final setting position placing the thrust members in unstable relation under conditions of use with the points of engagement at or adjacent to alignment; holding means holding the members in set position; devices releasing the holding means to facilitate a release movement of the thrust members; and means supplementing the devices compelling a release movement of the members.

9. In a wringer or the like, a frame; a pair of wringer rolls mounted in the frame; a pressure means exerting pressure on the rolls; a re-setting device for re-setting the pressure on the pressure means comprising members in thrust relation with each other and having connections with points of thrust engagement between them and the pressure means and the frame, one of the members being swingingly mounted and swinging on a fixed center to set the pressure means and through its swinging increase the thrust on the pressure means as the points of thrust engagement of the members approach centering alignment with the direction of thrust, said device having a manually engageable part for moving the members relatively to set position; and a separate manually responsive release device initiating a safety release of the pressure means.

10. In a wringer or the like, a frame; a pair of rolls mounted in the frame; a pressure means exerting pressure on the rolls; a re-setting mechanism for re-setting the pressure on the pressure means comprising members in thrust relation with each other and having connections with points of thrust engagement between them and the pressure means and the frame, one of the members being swingingly mounted and swinging on a fixed center to set the pressure means and through its swinging increase the thrust on the pressure means as the points of thrust engagement of the members approach centering alignment with the direction of thrust, one of the members including a lever for moving the members relatively to set position; and a separate manually responsive release device initiating a safety release of the pressure means.

11. In a wringer or the like, a swingable frame; a swinging mounting for the frame; a pair of rolls mounted in the frame; a pressure means exerting pressure on the rolls; a re-setting mechanism for re-setting the pressure on the pressure means comprising members in thrust relation with each other and having connections with points of thrust engagement between them and the pressure means and the frame, one of the members being swingingly mounted and swinging on a fixed center to set the pressure means and through its swinging increase the thrust on the

pressure means as the points of thrust engagement between the members approach centering alignment with the direction of thrust with the final setting position placing the thrust members in unstable relation under conditions of use with the points of engagement at or adjacent to alignment; holding means frictionally engaged holding the members in set position; and devices releasing the holding means to facilitate a release movement of the thrust members, said devices being responsive to a swinging of the frame.

12. In a wringer or the like, a swingable frame; a pair of wringer rolls mounted in the frame; a pressure means exerting pressure on the rolls; a re-setting device for re-setting the pressure on the pressure means comprising members in thrust relation with each other and having connections with points of thrust engagement between them and the pressure means and the frame, one of the members being swingingly mounted and swinging on a fixed center to set the pressure means and through its swinging increase the thrust on the pressure means as the points of thrust engagement between the members approach centering alignment with the direction of thrust, said members having a manually engageable element for moving the members to set position; and a separate manually responsive device initiating a safety release of the pressure means, said device being responsive to swinging of the frame.

13. In a wringer or the like, a frame; a pair of rolls mounted in the frame; a pressure means exerting pressure on the rolls; a driving means for the rolls having a releasable connection; a re-setting device comprising members in thrust relation with each other and having connections with points of thrust engagement between them and the pressure means and the frame, one of the members being swingingly mounted and swinging on a fixed center to set the pressure means and through its swinging increase the pressure on the pressure means as the points of thrust engagement between the members approach centering alignment with the direction of thrust, said members having a manually engageable part for moving the members to set position; a release device for initiating a release movement of the members; and mechanism automatically responsive to the re-setting device and the release device for re-setting and releasing the releasable connection.

14. In a wringer or the like, the combination of a frame mounted for bodily movement; a pair of wringer rolls mounted in the frame; a pressure means exerting pressure on the rolls; a driving means for driving the rolls comprising a releasable connection; manually operable devices for re-setting one of said means; and an independently manually actuated safety mechanism for releasing the means so re-set, said safety mechanism being responsive to the bodily movement of the frame.

15. In a wringer or the like, the combination of a frame mounted for bodily movement; a pair of wringer rolls mounted in the frame; a pressure means exerting pressure on the rolls; a driving means for driving the rolls comprising a releasable connection; manually operable devices for re-setting one of said means; a safety mechanism for releasing the means so re-set, said safety mechanism being responsive to the bodily movement of the frame; and mechanism automatically centering the frame to operative position as the re-setting mechanism is actuated.

16. In a wringer or the like, the combination

of a wringer frame; a pair of wringer rolls mounted in the frame; a movable mounting for the frame; pressure means for the rolls; driving means for the rolls; release devices for each of said means; a safety mechanism acting on one of said means responsive to frame movement; and a holding device yieldingly holding the frame in operative position and releasable by a pull or push on the frame, said holding device being more sensitive to a pull on the frame than a push on the frame.

17. In a wringer or the like, the combination of a wringer frame; a pair of wringer rolls mounted in the frame; a movable mounting for the frame; pressure means for the rolls; driving means for the rolls; release devices for each of said means; a safety mechanism acting on one of said means responsive to frame movement; a holding device yieldingly holding the frame in operative position and releasable by a pull or push on the frame, said holding device being more sensitive to a pull on the frame than a push on the frame; and a re-setting device for the means released, the re-setting device automatically resetting the holding means.

18. In a wringer or the like, a frame; a pair of rolls mounted in the frame; a movable mounting for the frame; a pressure means exerting pressure on the rolls; a re-setting mechanism for re-setting the pressure on the pressure means comprising members in thrust relation with each other and having connections with points of thrust engagement between them and the pressure means and the frame, one of the members being swingingly mounted and swinging on a fixed center to set the pressure means and through its swinging increase the thrust on the pressure means as the points of thrust engagement of the members approach centering alignment with the direction of thrust, with the final setting position placing the thrust members relatively in unstable relation under conditions of use with the points of engagement at or adjacent to alignment; holding means holding the members in set position; devices releasing the holding means to facilitate a release movement of the thrust members, said frame through its movement actuating said devices; and mechanism compelling a re-setting of the frame in operative position with a re-setting movement of the re-setting mechanism, said holding means yieldingly holding the frame in operative position.

19. In a wringer or the like, a frame; a pair of rolls mounted in the frame; a movable mounting for the frame; a pressure means exerting pressure on the rolls; a re-setting mechanism for re-setting the pressure on the pressure means comprising members in thrust relation with each other and having connections with points of thrust engagement between them and the pressure means and the frame, one of the members being swingingly mounted and swinging on a fixed center to set the pressure means and through its swinging increase the thrust on the pressure means as the points of thrust engagement of the members approach centering alignment with the direction of thrust, with the final setting position placing the thrust members relatively in unstable relation under conditions of use with the points of engagement at or adjacent to alignment; holding means holding the members in set position, said holding means being more sensitive to a pull on the frame than a push on the frame; devices releasing the holding means to facilitate a release movement of the thrust mem-

bers, said frame through its movement actuating said devices; and mechanism compelling a re-setting of the frame in operative position with a re-setting movement of the re-setting mechanism, said holding means yieldingly holding the frame in operative position.

20. In a wringer or the like, the combination of a frame; rolls mounted in the frame; a movable mounting for the frame; an indexing device permitting the positioning of the frame to different operative positions; a pressure means for the wringer; driving means for the wringer; a release device for one of said means; a re-setting device for the release device; devices automatically setting and releasing the indexing device with the setting and releasing of the release means; and means moving the frame to operative position relatively to the indexing device, said means being automatically responsive to the re-setting movement of the release means.

21. In a wringer or the like, the combination of a frame; rolls mounted in the frame; a driving means for the rolls having a releasable connection; an indexing device permitting the positioning of the wringer to different positions; means permitting a movement of the frame relatively to the indexing device; means responsive to a movement of the frame releasing the driving means and the indexing device; and means re-setting the driving means, said means automatically re-setting the indexing device and positioning the frame to operative position relatively thereto.

22. In a wringer or the like, the combination of a frame; rolls mounted in the frame; a pressure means; an indexing device; a release device for the pressure means; a re-setting device for the pressure means; means permitting relative movement between the indexing device and the frame; devices responsive to a movement of the frame operating the release device; and a positioning device putting the frame in operative position; and said devices including common actuating means in the frame of the wringer effective through movement thereof to actuate the indexing device, the release device and the re-setting device.

23. In a wringer or the like, the combination of a frame; rolls mounted in the frame; a pressure means; an indexing device; a release device for the pressure means; a re-setting device for the pressure means; a holding device holding the release device in set position; and said devices including a horizontal master rod in the frame of the wringer effective through its rotation actuating the indexing device, the release device, the re-setting device and the holding device.

24. In a wringer or the like, the combination of a frame; rolls mounted in the frame; a pressure means; a release device for the pressure means; a re-setting device for the pressure means; a holding device holding the release device in set position; and said devices including a horizontal master rod in the frame of the wringer effective through its rotation actuating the release device, the re-setting device and the holding device.

25. In a wringer or the like, the combination of a frame; rolls mounted in the frame; a pressure means for the rolls; driving means for the rolls having a releasable connection; a safety device breaking the driving connection; an indexing device permitting the moving of the wringer to different operative positions; and a hori-

zontal master rod extending lengthwise across the bottom of the wringer and operating from a point remote from the releasable connection controlling the safety device and the indexing device.

5 26. In a wringer or the like, the combination of a frame; rolls mounted in the frame; a pressure means for the rolls; driving means for the rolls having a releasable connection; a safety device for breaking the driving connection; an indexing device permitting the moving of the wringer to different operative positions; a movable mounting for the wringer frame and indexing device, said safety device being responsive to frame movement; positioning devices positioning the frame in operative position relatively to the indexing device; and a horizontal master rod controlling the safety device and the indexing device.

20 27. In a wringer or the like, the combination of a frame; an indexing device on which the frame is movably mounted; rolls mounted in the frame; pressure means for the rolls; driving means for the rolls having a releasable connection; a release device for the pressure means; a release device for the driving connection, said release devices being responsive to frame movement relatively to the indexing device; a re-setting device for the pressure means having an unstable relation under operative conditions; a holding means for holding the pressure device in set position; a positioning device positioning the frame in operative relation relatively to the indexing device; and said devices including a master rod controlling the release and re-setting of the pressure means, the driving means, the holding means, the positioning device and the indexing device.

40 28. In a wringer or the like, the combination of a wringer frame; rolls mounted in the frame; pressure means exerting pressure on the rolls; a driving means for the rolls; a safety device releasing one of the means, including a re-setting device for re-setting the means released; a movable mounting for the frame; a trip device communicating frame movement to actuate the safety device; and means compelling a centering of the frame as the safety device is re-set.

50 29. In a wringer or the like, the combination of a wringer frame; a movable mounting for the frame; rolls mounted in the frame; pressure means exerting pressure on the rolls; a driving means for the rolls; release devices for each of said means; a safety device actuated by a movement of the frame operating one of said release devices; a re-setting device re-setting the released means; and mechanism made active by the re-setting device in re-setting the released means re-positioning the frame in operative position.

60 30. In a wringer or the like, the combination of a wringer frame; a movable mounting for the frame; rolls mounted in the frame; pressure means for exerting pressure on the rolls; a driving means for the rolls; a device for causing the pressure means to exert or release pressure on the rolls; said device including a trip rod extending across the bottom of the wringer; and means responsive to a movement of the wringer frame for actuating the trip rod to cause said device to release pressure on the rolls.

70 31. In a wringer or the like, the combination of a frame; a movable mounting for the frame; rolls mounted in the frame; a pressure device exerting pressure on the rolls; a driving means for the rolls having a release connection there-

in; a safety release releasing the pressure device and the driving connection as the safety release is actuated; and means responsive to the movement of the frame actuating the safety release.

32. In a wringer or the like, the combination of a frame; a movable mounting for the frame; rolls mounted in the frame; a pressure device exerting pressure on the rolls; a driving means for the rolls having a release connection therein; a safety release releasing the pressure device and the driving connection as the safety release is actuated; means responsive to the movement of the frame actuating the safety release; and means for simultaneously resetting the pressure device and the release connection.

33. In a clothes wringer a main frame, a cover bodily separable therefrom to at least a limited extent, a roller mounted in said frame, a roller mounted in said cover, means for driving said rollers, a clutch including an axially slidable member for connecting and disconnecting one of said rollers from said driving means, latching means for attaching each end of said cover to a fixed portion of said frame, and a single manually operable means for concurrently controlling the application of pressure between said rollers and controlling the operation of all of said latching means and said clutch.

34. In a clothes wringer a main frame, a cover bodily separable therefrom to at least a limited extent, a pair of rollers housed within said frame and cover, means for driving said rollers, a clutch including an axially slidable member for connecting and disconnecting said rollers from said driving means, latching means for attaching said cover to said frame at a plurality of points, and a single manually operable means for concurrently controlling the application of pressure between said rollers and controlling the operation of all of said latching means and said clutch.

35. In a clothes wringer a main frame, a cover bodily separable therefrom to at least a limited extent, a roller mounted in said frame, a roller mounted in said cover, latching means for attaching said cover to said frame at a plurality of points, a manually operable lever for controlling all of said latching means, means for driving one of said rollers, and a clutch including a slidable member mounted independently of said rollers and controlled by said lever for connecting said driving means with said roller.

36. In a clothes wringer a main frame, a cover bodily separable therefrom to at least a limited extent, a roller mounted in said frame, a roller mounted in said cover, means for driving said rollers, a clutch including an axially slidable member for connecting and disconnecting said rollers from said driving means, latching means for attaching each end of said cover to said frame, spring means constantly engaging one of said rollers, and manually operable means shiftable with respect to said cover for concurrently causing said spring means to apply a pressure between said rollers and controlling the operation of said latching means and said clutch.

37. In a wringer of the type having an emergency release for the rolls thereof, driving means therefor and a clutch in said driving means, mechanism operating the clutch, cooperating rolls associated with the frame, a pressure mechanism for the rolls, a member carrying the driving means freely movable with respect to the frame, means for latching the member in operative position with the frame, a release device for said latching means operable by relative move-

ment between the member and frame, and a manually operated rotatable rod member for resetting the pressure upon the rolls following actuation of the release device and mechanism operated by the movement of said rod member for actuating the clutch operating mechanism to control the clutch in the driving means.

38. In a wringer or the like having a frame mounted for bodily movement, associated rolls, a safety release, and resetting means for operating and resetting the safety release, the combination of means biasing the resetting means toward released position, latch means for locking the resetting means against operation toward the released position, and means responsive to bodily movement of the frame for tripping the latch means.

39. In a wringer or the like having a frame mounted for bodily movement in response to a thrust, associated rolls, and a safety release, the combination of means biasing the safety release toward operation, latch means for locking the release against operation, a manually movable part for resetting the release and latch means by movement in one direction and for tripping the latch means by movement of said part in the reverse direction, and means responsive to bodily movement of the frame for moving said part in said reverse direction.

40. In a wringer having rolls, and a pressure mechanism for applying and releasing pressure to the rolls, the combination of means biasing the pressure mechanism to the released position, latch means for holding the pressure mechanism in the pressure position, a manually engageable part for resetting the pressure means by movement in one direction, and for tripping the latch means by movement of said part in the reverse direction, and means responsive to a thrust on the rolls for moving said part in said reverse direction.

41. In a wringer or the like, the combination of a frame; a movable mounting for the frame; rolls mounted in the frame; a pressure device for exerting pressure on the rolls; a driving means for the rolls having a releasable connection therein; a second device including means for operating the pressure device to apply pressure and to simultaneously establish the driving connection, said second device being also operable to release the pressure device and to simultaneously break the driving connection, and means responsive to movement of the wringer frame to operate the second device to release the pressure device and to break the driving connection.

42. In a wringer, drive gearing, an indexing device for positioning the gearing in different operative positions, a wringer frame, means mounting the frame for movement relative to the gearing, a safety release, actuating means for the safety release, and means responsive to the setting of the indexing device for conditioning the actuating means to respond to said relative movement.

43. In a wringer, the combination of a frame, a movable mounting for the frame, an indexing device permitting the positioning of the frame to different operative positions, a pressure means for the wringer, a release device for said means responsive to movement of the frame relative to its mounting, a resetting device for the release device, and devices automatically setting and releasing the indexing device with the setting and releasing of the release device.

44. In a wringer, the combination of a frame,

a movable mounting for the frame, an indexing device permitting the positioning of the frame to different operative positions, a pressure means for the wringer, a release device for said means responsive to movement of the frame relative to its mounting, and devices conditioning the release device for operation with the setting of the index device.

45. In a wringer, a frame, a movable mounting for the frame, a release device responsive to movement of the frame relative to its mounting on either side of a center position, an index device for maintaining the mounting in different operative positions, and means effective upon operation of the index device to position the wringer for centering the frame on its mounting.

46. In a wringer or the like of the type having an emergency release for the rolls thereof, reversing gearing, a handle for setting the gearing to drive the rolls in the desired direction, a 20 pressure mechanism for the rolls, manually operated safety release mechanism for relieving pressure between the rolls and setting the gearing to stop the rolls, and including a manually operated horizontally disposed rotating and actuating rod member extending longitudinally of the wringer and actuated by the handle for resetting the pressure and automatically resetting the gearing to drive the rolls in the desired direction following actuation of the release mechanism.

47. In a wringer of the type having a roll carrying frame, driving means for the rolls having a releasable connection therein, pressure mechanism for the rolls, means supporting the frame for movement relative to the driving means, an emergency release for the roll pressure operable by relative movement between the frame and driving means, latching means securing the driving means in operative position, a release device for the latching means operable by relative movement between the frame and driving means and including a manually operated rotatable rod member for resetting the pressure upon the rolls following actuation of the release device, and mechanism operated by the movement of said rod member for setting the connection to control the driving mechanism.

48. In a construction for a wringer having a frame, rolls and means supporting the rolls in pressure relation on the frame; an indexing device for setting the frame in any one of a plurality of radial positions, a lost motion connection between the indexing device and the frame limiting swinging of the frame relative to the indexing device to a plane, a safety release, means responsive to swinging of the frame relative to the indexing device for actuating the safety release, a resetting device for the safety release, and a connection between the resetting device and the index device for resetting the index device upon resetting of the safety release.

49. In a wringer having a roll receiving frame and roll reversing gearing settable to stop and start the rolls, a safety release, actuating means for the safety release responsive to a thrust on the rolls, and means responsive to the setting of

the gearing to start the rolls for conditioning the actuating means to respond to a thrust on the rolls.

50. In a wringer having a roll receiving frame 5 and a safety release responsive to a thrust on the rolls, an index device for positioning the wringer in any one of a plurality of radial index positions, locking means for the index device effective when locked to prevent and when unlocked 10 to permit movement of the wringer from one index position to another, and means for locking and unlocking the locking means with the setting and releasing of the safety release.

51. In a wringer having a roll receiving frame and a safety release responsive to a thrust on the rolls, an index device for positioning the wringer in any one of a plurality of radial index positions, locking means for the index device effective when locked to prevent and when unlocked 15 to permit movement of the wringer from one index position to another, and means for unlocking the locking means for the index device with the release of the safety release.

52. In a wringer having a roll receiving frame 25 and a safety release responsive to a thrust on the rolls, an index device for positioning the wringer in any one of a plurality of radial index positions, locking means for the index device effective when locked to prevent and when unlocked 30 to permit movement of the wringer from one index position to another, a drive for the rolls settable to stop and start the rolls, means for unlocking the locking means for the index device with the release of the safety release, and means for locking the locking means with the setting of 35 the drive to start the rolls.

53. In a wringer having a roll receiving frame, an indexing device for positioning the wringer in different operative positions, a safety release, latch means holding the release in set position, actuating means for tripping the latch means in response to a thrust on the rolls, and means conditioning the actuating means to respond to a thrust upon setting of the indexing device.

54. In a wringer, a frame for receiving rolls, a movable mounting for the frame, a drive, a safety release for the drive, means responsive to movement of the frame on its mounting for actuating the release, means supporting the mounting for 40 swinging to a plurality of positions, an indexing device for setting the mounting in any one of said positions, and means setting and releasing the index device with the setting and releasing of the release device.

55. In a wringer having a roll receiving frame 45 and a drive for the rolls settable to stop and start the rolls, an index device for positioning the wringer in any one of a plurality of positions, a safety release for the drive, actuating means for the release responsive to a thrust on the rolls, other actuating means for releasing the index, and an interlock between the index and drive compelling release of the drive upon release 50 of the index.

CARL MOON.
